UNITED STATES PATENT OFFICE.

JOSEPH S. HEALEY, OF EAST WEYMOUTH, ASSIGNOR TO STILES FROST, OF NEWTON, MASSACHUSETTS.

ANTI-RATTLER FOR THILL-COUPINGS.

SPECIFICATION forming part of Letters Patent No. 223,731, dated January 20, 1880.

Application filed May 19, 1879.

To all whom it may concern:

Be it known that I, JOSEPH S. HEALEY, of East Weymouth, in the county of Norfolk and State of Massachusetts, have invented an Improvement in Anti-Rattling Shaft-Holding Springs, of which the following is a specification.

This invention relates to a coiled spring to prevent shaft-shackles upon vehicles from rattling as the bolt becomes worn, or if the bolt fails from any cause to properly fit the shaft-iron.

Figure 1 represents this invention applied to an ordinary shaft-shackle; Fig. 2, the spring in perspective.

It is well known that shaft-couplings when first made, if loosely fitted, or after being worn a short time, rattle. To overcome this difficulty many vehicles are supplied with shaft-shackles specially constructed, and thereby made expensive, to prevent rattling. One most common plan for this purpose is the insertion of a yielding block of india-rubber. Flat steel springs have also been used.

The spring herein described, and constituting an improved article of manufacture, is composed of a single piece of wire bent, as herein shown and described, to form a spring, and so as to embrace the rear portion of the shaft-iron, and so as to hook over the forwardly-projecting side ears of the clip. The wire is coiled at *d g* to form two short springs, one in line with the other. The central portions, *e f*, extended therefrom, are curved to fit the rounded portion, *j*, of the shaft-iron, and the end portions, *i h*, made to diverge as they leave the coiled portions *d g*, are provided with hooks *a b*, bent so as to extend parallel with the axes

of the coils and the bolt holding the thills in the clip.

The eye *j* of the shaft-iron *k* is entered by the bolt *l*, carried by the clip part *c*, attached to the axle *n*, as usual. The spring is inserted between the clip and the convex portion of the eye *j*.

These springs are intended to be applied to ordinary shaft-shackles. I find it impossible to retain the springs in place for any length of time unless the hooks *a b* engage the side ears, *m n*, of the clip part. The small horizontal ledge formed on the clip part immediately at the front of the axle is, I have found in practice, insufficient.

I do not broadly claim a wire spring irrespective of its special construction and adaptation.

I claim—

As an improved article of manufacture, an anti-rattling shaft-holding spring composed of a single piece of wire bent as shown, the portions *e f* being curved to fit the rounded eye part of the shaft-iron, and the hooked ends *a b* of the diverging portions *h i* being bent outward in the direction of the axes of the coils *d g*, so as to engage the forwardly-projecting side ears of the clip part which holds the bolt, all as and for the purpose substantially as described.

In testimony whereof I have signed my name to this specification in the presence of two subscribing witnesses.

JOSEPH S. HEALEY.
